CLAIM

The ornamental design for a case for electronic communication device, as shown and described.

DESCRIPTION

FIG. 1 is a front, left, and top perspective view of a case for electronic communication device showing my new design; FIG. 2 is a rear, right, and bottom perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; FIG. 8 is a bottom plan view thereof; FIG. 9 is a perspective view of the case for electronic communication device where a kickstand of the case for electronic communication device is in an open position; FIG. 10 is a perspective view of the case for electronic communication device where the case for electronic communication device is in a folded state; and, FIG. 11 is an exploded perspective view of the case for electronic communication device where a pen is separated from a main body. The broken lines in the drawings represent portions of the case for electronic communication device that form no part of the claimed design.

1 Claim, 11 Drawing Sheets
